UNITED STATES PATENT OFFICE.

EDWARD E. WHITMORE, OF CHICAGO, ILLINOIS, ASSIGNOR TO THE CURTAIN SUPPLY COMPANY, OF CHICAGO, ILLINOIS, A CORPORATION OF ILLINOIS.

CAR-VESTIBULE DIAPHRAGM.

1,249,870.

Specification of Letters Patent. Patented Dec. 11, 1917.

Application filed April 28, 1916. Serial No. 94,087.

To all whom it may concern:

Be it known that I, EDWARD E. WHITMORE, a citizen of the United States, residing at Chicago, in the county of Cook and State of Illinois, have invented certain new and useful Improvements in Car-Vestibule Diaphragms, of which the following is a specification.

The invention has for its special object the provision of an improved diaphragm face plate adapted particularly for use in connection with metallic diaphragms, wherein the rigidity of the same and resistance to strain incident to the support of the diaphragm and shocks in service is retained and even enhanced while permitting of a reduction in the total weight of the car end diaphragm construction far overbalancing the added weight due to the use of the metallic diaphragm instead of the old form of accordion plaited belting.

The ordinary diaphragm face plate, in order to secure the necessary strength, is seven-eighths inch or one inch in thickness and weighs in the neighborhood of 600 pounds, which weight, in addition to that of the diaphragm proper, must be carried by the reciprocating spring pressed stems. The wear is considerable and in a short time causes a sagging of the face plate and resultant speedy disintegration of the diaphragm plaits especially at the upper corners, necessitating blocking up or other unsatisfactory expedients.

The use of the metallic diaphragm, such as that of United States Patent No. 1,167,973, issued to Brown, has found favor with the railroads, but an objection urged against all metallic diaphragms is the greater weight over diaphragms of the belting type, which increased weight added at both ends of the car is to be avoided if possible.

In the attempt to overcome this objection I have sought to decrease the weight of the heavier part, *i. e.* the face plate, without sacrifice of strength by utilizing structural features of the metallic diaphragm to reinforce a lighter face plate, thus effecting a useful coöperation between the two parts of the diaphragm which results in the production of a metallic diaphragm materially lighter instead of heavier than the belting

type, and which, at the same time, has greater resistance to wear and violent shocks in service.

In order that the invention may be readily understood the same is set forth in the accompanying drawing and in the detailed description as embodied in a metallic diaphragm of the Brown type. It will be understood, however, that the invention is not limited to diaphragms of this type as the essential features thereof may be employed in various embodiments.

In the drawing—

Figure 1 is a side elevation of a car end diaphragm construction embodying the invention;

Fig. 2 is a transverse section on the line 2—2 of Fig. 1; and

Figs. 3, 4, and 5 show in cross section modified forms of face plates and connection to the diaphragm side walls.

As illustrated, the car end plate is shown at 11 attached to the end post 12 and carrying diaphragm side members 13 of inverted U-shape forming continuous side and top walls. The side and top walls 13 have outwardly extending flanged portions 14 co-operating with similarly flanged portions 15 of the side and top diaphragm members 16 whereby telescopic action of the members 13 and 16 is provided for, as will be readily understood. Rigidly connected with the diaphragm members 16 is a diaphragm face plate 17, carried by stems 18 and 19 spring pressed and mounted for longitudinal reciprocation as is usual. Preferably, the face plate 17 is an integral continuous structure having the side portions 17^a, the bottom portions 17^b and the top portions 17^c. The general contour of the face plate in elevation is that of the diaphragm proper, the diaphragm members 16 being fixedly joined to the rear of the face plate either by being formed integral therewith or riveted thereto, and preferably along the median longitudinal line thereof, as indicated in Fig. 2.

The rigid fixed connection between the diaphragm face plate 17 and the diaphragm side and top wall members 16 constitute of the diaphragm members 16 an effective reinforcement for the face plate 17, thus enabling the latter to be formed of sheet metal

suitably stamped, pressed or rolled as distinguished from the heavy face plate hereinafter used.

As an additional reinforcement the face plate 17 may be provided throughout its extent with marginal reinforcing ribs 20 upon either its inner or outer margins or both, these marginal reinforcing ribs supplementing the diaphragm members 16 which are, in a sense, also reinforcing ribs of the face plate 17.

In Fig. 3 a form of construction is illustrated in which the diaphragm member, lettered 16*, is formed integral with the face plate 17, the latter being folded upon itself in a median plane and advantageously joined by rivets 21.

In Fig. 4 the face plate 17 is shown as provided with a median reinforcing rib 22 to which the diaphragm member 16 is secured by rivet 23.

In Fig. 5 the face plate 17 is shown as provided with both the integral median rib 22 and the marginal ribs or flanges 20, the diaphragm member 16 being joined to the rib 22 by the rivets 23 as in Fig. 4.

I claim:

1. In a car vestibule construction, the combination with a sheet metal face plate having formed integral therewith a longitudinal reinforcing rib, and metallic diaphragm side walls rigidly joined to said face plate and reinforcing said plate.

2. In a car vestibule construction, the

combination with a marginally flanged sheet metal face plate, and metallic diaphragm side members rigidly joined to said face plate and additionally reinforcing said plate.

3. In a car vestibule construction, the combination with a sheet metal face plate having continuous side, bottom and top portions with marginal reinforcing flanges, and metallic diaphragm side and top walls rigidly joined to the face plate along a medial line thereof and additionally reinforcing said face plate.

4. In a car vestibule construction, the combination with a sheet metal face plate provided with an integral longitudinal reinforcing rib, and diaphragm side walls joined to said face plate by means of said rib.

5. In a car vestibule construction, the combination with a sheet metal face plate having continuous side and top portions, and metallic diaphragm side and top walls rigidly joined to the face plate along a medial line thereof and reinforcing said plate, said face plate also provided with marginal reinforcing ribs.

In witness whereof I have hereunto signed my name in the presence of two subscribing witnesses.

EDWARD E. WHITMORE.
